FLAT TYPE SWITCH

Hans Sengebush, Villa Park, Ill., assignor to Automatic Electric Laboratories, Inc., Chicago, Ill., a corporation of Delaware

Application July 12, 1951, Serial No. 236,377

9 Claims. (Cl. 179—27.52)

1

The present invention relates to switching apparatus for telephone systems, and more particularly to switches which are adapted for step-by-step motion in each of two directions.

One of the objects of this invention is to provide a flat type switch which is capable of moving a plurality of contact wipers in a selective number of rotary and radial steps.

Another object of this invention is to provide a combination drive and release mechanism for this switch which requires only two electromagnetic motor units.

Another object of the invention is the provision of a novel locking linkage which is adapted to cooperate with the driving mechanism to change the direction of movement of the contact wipers.

A further object of this invention is the use of this novel locking linkage in maintaining the contact wiper support or carriage in a stationary position whenever the wipers have been moved to a position which is off-normal with respect to such support.

A further object of this invention is a provision for a new system whereby the radial position of the wipers can be ascertained from a position remotely located with respect to said wipers.

A still further object of the invention is to provide a new frame for supporting a plurality of switches for this type in a vertical direction and for supporting a plurality of bank assemblies in aligned position therewith.

Other objects and features of this invention will be brought out more clearly upon a perusal of the following specification and drawings in which: Fig. 1 is a plan view of the switch mounted in a framework which is provided with one of the novel contact bank assemblies which may be used therewith; Fig. 2 is an enlarged detail plan view of the driving mechanism; Fig. 3 is a sectional view taken along line 3—3 of Fig. 1; Fig. 4 is the bottom view of the driving segment and contact wiper support carriage; Fig. 5 is a segmentary perspective view of the locking linkage and a portion of a radial indicator linkage; Fig. 6 is a perspective view of a portion of the framework which is adapted to maintain the contact bank assemblies in aligned position for a vertical stack of a plurality of switches of the general type described herein; Fig. 7 is a side view of the one of the bank assemblies; and Fig. 8 is an enlarged sectional view taken along line 8—8 of Fig. 7.

The particular embodiment of the switch disclosed herein is capable of performing any of the well known functions of two motion switches,

2

such as telephone linefinders, selectors and connectors. This switch is further adapted for selecting any one of two hundred groups of four conductors each, which are disposed about the switch in banks of insulated bare wires.

Referring now more particularly to Figs. 1, 3 and 6, the apparatus comprises a framework 10 upon which a plurality of switches 11, of the type more specifically described hereinafter, are stacked in vertical direction. The framework 10 is also adapted for maintaining a plurality of bank contact assemblies 12 in aligned position and arcuately disposed with respect to the switches 11. Each of the switches 11 includes an assembly of contact wipers 13, or as shown in the preferred embodiment, two assemblies of contact wipers 13 which are arranged to be rotated about a central post 14 until such contact wipers 13 are in alignment with a desired contact bank assembly 12. The wiper assemblies are each slidably mounted on a bar 15 so that they may be moved radially, with respect to the switch, into contact with the elements of the bank assembly 12, as will be more specifically shown herein-after.

Considering now the structure of the switch apparatus in greater detail, reference should be made to Figs. 1, 2, 3, 4 and 5 in which a base plate 16 is provided and upon which all of the switch components described hereinafter are mounted. A vertical post 14 is secured to this plate 16 in any suitable manner, such as riveting. A driving segment 17, for actuating the component members of the switch, is mounted on the vertical post 14 for rotational movement thereabout in any suitable manner known in the art. The preferred embodiment shows this accomplished by a suitable bushing 18 which is adapted for rotation on the post 14 and which is securely fastened to the driving segment 17 in any well known manner, such as by riveting the upper rim of the bushing to the segment. An indicator arm 19 is adapted for rotational movement about the post 14 and may be positioned, as shown in Fig. 3, to rotate about the bushing 18. A support plate or carriage 20 is also mounted for rotational movement about the post 14 and is preferably fastened to a collar 21, which in turn is adapted to engage post 14 and rotate thereabout. If it is deemed desirable, the collar 21 may be separated by the bushing 18 by a suitable spacer 22. All of these components which are mounted on the post 14 are secured thereon in any well known manner, the preferred embodiment demonstrating the use of a washer 23 and machine screw 24.

The driving segment 17 and carriage 20 are rotatively biased toward one another in any manner deemed desirable. This can be accomplished through the use of a spring 25 which is fastened to a post 26 and a post 27, which posts are mounted on the carriage 20 and the segment 17 respectively. The biasing effect on the spring 25 is limited by the use of a stop 28 mounted on the carriage 20 by machine screws 29. Segment 17 is also rotatively biased in a clockwise direction as viewed in Fig. 1. This is accomplished by means of spring 25A. In Fig. 4, the biasing effect of the spring 25A is shown as rotating the segment 17 in a counterclockwise direction. In normal position the stop 28 on the carriage 20 engages a stop 30 fastened to the base 16 to limit the counterclockwise rotation of carriage 20 and segment 17 as seen in the bottom view of Fig. 4. The spring 25A is maintained under tension at all times.

For additional co-operation between the segment 17 and the carriage 20 there is a lock bar 31, which is preferably fabricated from some resilient material, and is fastened to the carriage 20 by machine screws 32. The lock bar 31 is provided with a projection 33 which extends downwardly therefrom and which is disposed to engage a slot 34 in the segment 17. The lock bar 31 is tensioned so that its normal action is biased downward with respect to the carriage and is arranged such that when it is at rest, with its body against carriage 20, the projection 33 is extended through the slot 34 in the driving segment 17. Thus the driving segment 17 and carriage 20 are rotatively biased toward one another and are mechanically locked together for rotational movement.

The outer end of the lock bar 31, as is seen in Fig. 5, is provided with one or two upturned projections 35. The projections 35 are adapted to engage a plurality of radially spaced teeth 36 which are provided in a lock segment 37. In turn, the lock segment 37 is mounted on the base plate 16 in any suitable manner, such as with machine screws 38 in Fig. 1. The height of the lock segment 37 is adjusted so that the projections 35 of the lock bar 31 are free therefrom when the lock bar 31 is in its normal position. A lock bar actuator 39 is pivotally mounted on the lock segment 37 in any suitable manner, such as bearing pin 40. The bearing pin 40 engages bearing holes in the lock bar actuator 39 and is rigidly fastened to the sides of the lock segment 37. The actuator 39 has an upwardly extending projection 41 to which any suitable biasing means, such as spring 42, may be attached. One end of the spring 42 is fastened to the actuator projection 41 with a rivet 43A and the other end of the spring 42 is fastened to the base plate 16 by a machine screw 43. The plane of the actuator 39 is disposed to lie beneath the tip of the lock bar 31. When the actuator 39 is rotated about its bearing pin 40, it contacts the outer end of the lock bar 31 and forces the lock bar upward so that the projections 35 engage the teeth 36 of the segment 37. The projections 35 of the lock bar and the lower projection 33 are further adjusted so that the lower projection 33 is disengaged from the segment slot 34 when the upper projections 35 are engaging the teeth 36. Thus when the lock bar actuator 39 is rotated about its bearing pin 40, the carriage 20 is rigidly fastened to the base 16 through the media of the lock bar 31 and locking segment 37. At the same time, the driving segment 17 is freed from its attachment to its car-

riage 20 and may thereafter be further rotated with respect to both the base 16 and the carriage 20.

In order to simplify the linkages used, the tension normally present in spring 42 is adjusted so that the bias placed upon the actuator 39 through its arm 41 is sufficient to overcome the bias of the lock bar 31. This results in the lock bar 31 being held in engagement with the locking segment 37 and out of engagement with the driving segment 17.

The preferred embodiment demonstrates the use of two lock bar projections 35 which are spaced a sufficient distance apart to span two of the lock segment teeth 36. By adjusting the projections 35 to lie at an angle slightly off-normal, the lock bar will readily engage the teeth 36 without bind, due to the increased distance between the tips of the projections 35. Continued movement of the lock bar in engaging the lock segment will force the teeth between the tilted projections until they are in tight engagement therewith. This permits close control of each of the several positions at which the carriage 20 may be locked to the base 16, as will hereinafter be seen desirable. Referring now to Fig. 1, a change-over magnet 44 is provided for operating the locking linkage described above and includes a suitable magnetic structure 45. The magnet 44 also includes a suitable armature 46 which is pivotally mounted on a bearing pin 47, which in turn is fixed to the magnetic structure 45. The armature 46 is provided with an outwardly extending arm 48 which is disposed to engage the actuator arm 41. When the magnet 44 is electrically energized by any suitable power source (not shown), the armature 46 is pivotally moved about its bearing pin 47. The armature 46, in turn, moves the arm 48 in a clockwise direction, as seen in Fig. 1, and causes the arm 48 to engage the actuator arm 41 and move the actuator about its bearing pin 40 against the bias of the spring 42. The lever arms of these various linkage members are fixed so that the actuator 39 is moved a sufficient amount to permit the bias of the lock bar 31 to become effective in disengaging the lock bar 31 from the locking segment 37 and move the projection 33 into engagement with slot 34 of the driving segment 17. Control circuits can be electrically connected to the magnet 44 for breaking the electrical circuit thereto at any desired time. The particular embodiment of the invention shown herein has provided for rotational movements of the carriage 20 and the driving segment 17 together for a series of up to ten stops as the magnet 44 is energized. At the end of any one of these ten steps, the control circuit (not shown) may remain open causing the release of the magnet 44 which in turn, by means of the locking linkage described above, will cause the lock bar 31 to lock the carriage 20 to the base 16 and free the driving segment 17 for rotational movement without rotation of carriage 20. If it is so desired, a post 49 may be rigidly fixed to the base 16 and be disposed to engage the surface of a projection 50 of the carriage 20 after the carriage 20 has been rotated ten steps about the post 44. This will serve as a limit stop in order to insure the carriage 20 from being rotated more than the predetermined distance.

A motor magnet 51 is secured to the base 16 in any well known manner and is provided with a suitable magnetic structure 52. The motor magnet 51 is further provided with an armature 53 which is pivotally mounted on a bearing pin 54

that is attached to the magnetic structure 52. As can be more clearly seen in Fig. 2, a pawl bearing pin 55 is attached to the outer end of the armature 53 and a stepping pawl 56 is pivotally attached to such pin 55. A bias spring 57 engages projections of the pawl 56 and the armature 53 in order to bias the pawl 56 in a clockwise direction about the pin 55 as viewed in Figs. 1 and 2. The pawl 56 is provided with a driving surface 58 at its outer end, which surface 58 is disposed to engage a series of ratchet teeth 59 that are disposed along the periphery of the driving segment 17. When the motor magnet 51 is electrically energized by any suitable control circuit (not shown), the armature 53 is attracted and pivotally moved about its bearing pin 54. This action moves the pawl 56 into engagement with one of the ratchet teeth 59, causing the rotational movement of the driving segment 17. As is well known in the art, a pawl stop 58A is attached to the base 16 and is disposed to limit the movement of the pawl 56 when it is driving the segment 17 one step. The position of the stop 58A is preferably adjustable so that the distance through which the segment 17 is rotated in one step can be closely adjusted. For the purpose of maintaining the driving segment 17 in its rotated position, a detent 60 is pivotally mounted on the base 16 by a suitable bearing 61. The detent 60 is provided with a projection 62 which is disposed to engage one of the ratchet teeth 59. The preferred arrangement shows the projection 62 engaging the tooth 59 that is immediately behind the tooth 59 which is engaged by the pawl 56. A bias spring 63 is attached to the base 16 by a bracket 64 and is disposed to engage an upwardly extending projection 65 of the detent 60. The effect of the spring 63 is to rotate the detent 60 about its bearing pin 61 and force the projection 62 into engagement with the ratchet tooth 59. It will be noted that spring 63 is moved a distance sufficient to open its break contacts and to close its make contacts only if magnet 44 is energized while the switch is in an off normal position.

The armature 46 of the change-over magnet 44 is provided with a second arm 66, the end of which has a bearing pin 67 attached thereto. A release pawl 68 is pivotally attached to the bearing pin 67 and is biased in a clockwise direction, as viewed in Figs. 1 and 2, about the bearing pin 67 by any suitable means, such as the spring 69. The outer end of the release pawl 68 has a detent 70 which is adapted to engage the upwardly extending projection 62 of the driving segment detent 60. In accordance with one of the objects of this invention, a pin 71 is attached to the driving segment 17 and is disposed to extend downwardly therefrom to intersect the plane of the pawl 68. The pin 71 will contact the detent end of the pawl 68 and force it out of engagement with the projection 62 of the detent 60 whenever the detent end 58 of the driving pawl 56 is engaged with the first ratchet tooth 59 of the driving segment 17.

When the driving segment is positioned off-normal, the biasing effect of the spring 69 causes the pawl 68 to move into engagement with the detent 60. If the change-over magnet 44 is energized while the driving segment is off-normal, the release pawl 68 is actuated to pull the detent projection 62 out of engagement with the ratchet 59 of the segment 17. During the releasing motion, the projection 62 engages the outer end of the driving pawl 56 and continued motion of the release pawl 68 and the detent projection 62 forces the detent end 58 of the driving pawl

56 out of engagement with the ratchet teeth 59. During the release motion projection 62 of detent 60 is rotated so as to operate the contacts of spring 63. This operation of the change-over magnet 44 fully releases the driving segment 17 of all obstructions and permits the return of the driving segment to its normal position under the biasing of spring 25. As the driving segment 17 traverses the distance from the second to the first step, the pin 71 again engages the detent end of the release pawl 68. Further movement of the driving segment in restoring to its normal position forces the pawl 68 out of engagement with the detent 60. This permits the detent 60 and the pawl 56 to re-engage the ratchet teeth 59 and the driving segment, and also permits the contacts of spring 63 to restore.

If the change-over magnet 44 is energized before the driving segment 17 is rotated from its normal position, the release pawl 68 will not engage detent 60, due to the effect of pin 71. If the motor magnet 51 is then energized to rotate the driving segment 17 off-normal, the release of the detent end 70 of the release pawl 68 by the driving segment pin 71 is of no consequence because the detent surface of the pawl 68 has been moved beyond the position in which it could engage the detent 60.

It will now be recalled that when the change-over magnet 44 is operated, the carriage 20 is locked to the driving segment 17 by means of the lock bar 31. Thus, when the change-over magnet 44 is operated before the energization of the motor magnet 51, the carriage 20 will be rotated 35 with the driving segment 17 during the operation of the motor magnet 51. If the change-over magnet is released after the driving segment 17 has been moved off-normal by the motor magnet 51, a subsequent reoperation of the motor magnet 51 will rotate the driving segment 17 alone, as the carriage 20 has been disconnected from the driving segment and locked to the base 16, as described above. It will also be noted that upon release of the change-over magnet 44, the release pawl 68 is once again moved upward with respect to the detent 60 and, since the driving segment is off-normal, is in position for releasing the detent 60 and the driving pawl 56 upon reoperation of the change-over magnet 44 as described above.

As described above, operation of the change-over magnet 44, after the carriage has been locked in a position off-normal and the segment has been further rotated with respect thereto, will release 55 both the driving segment, via the release pawl 68, and the carriage, via the lock segment actuator 39. The lock bar will not, at this moment, be disengaged from the lock segment. The lower projection 33 of the lock bar 31 is disposed to rest 60 on the surface of the driving segment 17 whenever the driving segment is in a position off-normal with respect to the carriage 20. The length of the projection 33 is adjusted so that when it is resting on the segment 17, the upper projections 35 of the lock bar are maintained in engagement with the lock segment teeth 36. Thus, when the change-over magnet 44 is actuated to release the switch, only the driving segment will rotate toward its normal position. When the driving segment 17 reaches its normal position with respect to the carriage 20, the slot 34 will be disposed beneath the lower lock bar projection 33. At this time the biasing action of the lock bar 31 will move the upper lock bar projections 35 out 70 of engagement with the lock segment teeth 36.

and the projection into engagement with slot 34. The segment 17 and the carriage 20 will then be locked together and returned to normal as a unit under the biasing action of the spring 23A.

The wiper assemblies 13, which are mounted on the carriage 20, will now be described in detail. While this particular embodiment of the invention discloses the adaptation of this switch for use as a 200 line switch, it is to be understood that the invention herein could readily be adapted for use with any reasonable number of lines by revision by any one skilled in the art. The carriage 20 is provided with two wiper mounting bars or mono-rails 15 which are rigidly fastened to the carriage by any suitable means. A plurality of contact wipers 72 are assembled and mounted together with suitable insulating spacers 73, as is well known in the art. This plurality of wipers 72 and insulators 73, which comprise the wiper assembly 13, are held together by any suitable means, such as screws 74. The screws 74 are also connected to racks 75 by means of flanges 76 which extend upwardly from the racks 75 into engagement with the screws 74. The wiper assemblies 13 together with the racks 75 are slidably mounted upon the rails 15 and may be fixed thereto for radial movement with respect to the carriage 20, by any suitable mono-rail guides 77. Each of the wipers 72 is provided with a terminal 78 which may be connected to any suitable, flexible lead wire (not shown).

The wiper assembly racks 75 are preferably disposed in close proximity to the surface of the carriage 20, where they are engaged by a gear 79. The gears 79 are mounted on an axle 80 which extends through bearing holes in both the carriage 20 and a suitable bracket 81, which is mounted on the carriage 20. The portion of the axle or shaft 80 which is protruding from the under side of the carriage is fixed with a suitable gear 82 in any manner known in the art. The gear 79 and the gear 82 are each rigidly fastened to the shaft 80 and are adapted for rotational movement therewith. The gear 79 engages the rack 75 of the wiper assembly 13 and is arranged to slidably move the wiper assembly along the mono-rail 15 when the gear 82 is rotated. As can be seen in Fig. 4, the portion of the driving segment 17 which is disposed opposite the gears 82 is provided with a series of teeth 83 which engage the teeth of the gears 82. When the driving segment 17 is rotated with respect to the carriage 20, the segment teeth 83 are correspondingly moved with respect to the gears 82 and thereby rotate the gears 82. As described above, this rotational movement will in turn slidably move the wiper assemblies 13 along the mono-rails 15.

Referring to Fig. 3, in order to adapt this switch for use with groups of four conductors each, it will be noted that the upper pair of contact wipers 72 are shorter in length than the lower contact wipers. When the wipers are moved radially outward with respect to the switch over the mono-rail 15 one step, the lower contact wiper will slide over the first contact of the contact bank 12 and will come to rest on the second contact thereof. The upper contact is adjusted in length so that it comes to rest on the first contact at this time. The stepping distance of the contact wiper assembly 13 is adjusted so that the upper contact wiper will come to rest on every other bank contact when driven one step at a time. In order to prevent each pair of lower and upper contact wipers from coming into contact with each other when they are

not engaging the contact bank 12, the carriage is provided with a post 84 which is made of any suitable insulating material. The tips of the contact wipers 72 are provided with off-set wiper tips which engage the post 84. This will force the wipers apart just as they are being disengaged from the contact bank.

Referring to Fig. 1, this switch is also provided with a pair of indicator arms which will indicate, at any time on a suitable scale 85, the position of the contact wipers. The scale 85 may comprise an upwardly extending flange of the base 16 which is arcuately shaped and which is engraved or otherwise marked with equally spaced notches and designating numbers. The carriage 20 has an indicator arm 86 which extends outwardly therefrom and is disposed directly above the scale 85. The end of the indicator arm 86 is provided with a suitable indicating line or notch and is moved a distance equal to the distance between two of the indicating notches of the scale 85 for every rotary step of the carriage 20.

The driving segment 17 is provided with an indicator arm 19 which normally lies directly below the indicator arm 86, which is adapted to rotate about the post 14. Indicator arm 19 has a projection 87 which is disposed to lie directly beneath the lock bar 31 when the switch is in its normal position. As can best be seen in Fig. 5, a portion of this projection 87 is provided with an upwardly extending tooth 88 which is engageable with any one of a series of small rectangular holes 89 in the driving segment 17. The projection 87 is also provided with an extension 90. This extension 90 extends through an opening in the driving segment and a portion thereof is disposed to lie above the section of the driving segment which is provided with the small rectangular holes 89. The lower projection 33 of the lock bar 31 is provided with a notch 91 which is disposed to engage the outer portion of the extension 90. The outer surface of the extension 90 is arcuately shaped to conform with the arc described by the lower lock bar projection 33 during its rotational movement. The lock bar notch 91 will move the extension 90 upward and downward with it when the lock bar is so operated and will, in turn, affect upward and downward motion of the projection 87 and the tooth 88. When the driving segment 17 and carriage 20 are rotated as a unit, the lock bar 31 is biased downward and maintains the projection 33 of the indicator arm 19 out of engagement with the driving segment notches 89. When the change-over magnet 44 is released, preparatory to moving the wipers radially outward, the lock bar 31 is moved upward and its notch 91 carries the extension 90 in the same direction. This causes the projection 87 to engage hole 89 which is then disposed directly above it. Further rotational movement of the driving segment 17 will then rotate the indicator arm 19 about the post 14 for the first time. Since this is also the initial radial movement of the contact wipers 13, the indicator arm 19 will directly indicate on the scale 85 the number of radial steps which have been taken by the wipers. Since the carriage 20 is not rotated after the radial movement of the wipers has begun, the indicator arm 86 will indicate, on the scale 85, the rotary position of the wipers. Thus at any time, mere observation of the scale 85 and the position of the indicator arms 19 and 86 will disclose the operated condition of the switch and the rotary and radial position of the contact wipers.

In order to satisfy all of the conditions under which two motion switches are required to operate and to satisfy the requirements thereof, numerous electrical contact spring assemblies have been provided which may be used when conditions require such. It is felt that the function and operation of all of these spring assemblies are well known in the art. Therefore they will not be described in great detail.

Referring to Fig. 1 the motor magnet 51 is provided with an interrupter spring assembly 101 which is actuated, to make or break electrical contact, by buffer arm 102. An insulating buffer 103 is attached to the buffer 102 to move an armature spring of the assembly 101 whenever the armature 53 is moved by the magnet 51. These interrupter springs may be utilized in case the switch is used as a selector switch in which case the magnet 51 may operate automatically to cause the switch to seize a first idle set of contacts. Springs 105 are mounted on the magnet structure 45 of the change-over magnet 44 for operation by the buffer arm 106 of the armature 46. Off-normal springs 107 are actuated by a buffer 108 which is fixed to the indicator arm 86 of the carriage 20. This same buffer 108 may be used to actuate a group of rotary cam springs 109. Radial off-normal springs 110 are operated by a projection 111 of the radial indicator arm 19. One or more groups of normal post springs 112 and 113 may be operated by a normal post plate 114 which is attached to the carriage 20.

From the foregoing, the operation of the present embodiment of the invention is apparent. Initially magnet 44 is energized. This unlocks the carriage 20 from the lock segment 37 and causes the carriage to be locked to the driving segment 17 by means of lock bar 31. Magnet 51 is then energized and restored a selected number of times causing the pawl 56 to directly step the driving segment 17 a selected number of steps in a counterclockwise direction as seen in Fig. 1. This results in the alignment of the wipers with selected groups of bank contacts such as 12 in the bank. Then magnet 44 is deenergized, causing the carriage 20 to be locked to the lock segment 37 and unlocked from the driving segment 17 by said bar 31. Magnet 51 is then energized and restored a second selected number of times causing the pawl 56 to directly step the driving segment 17 a second selected number of steps in a counterclockwise direction as seen in Fig. 1. This second rotation of the driving segment 17 is communicated by the gear teeth 83 to the pinions 62, in Fig. 4, and from the pinions 62 to the gears 79, and in turn to the racks 75 to cause the wipers to move in a radial direction into the selected groups of bank contacts. This results in the selection of a particular set of bank contacts by said wipers.

To cause the switch to restore, magnet 44 is then energized. This causes, as seen in Fig. 2, the release pawl 68 to draw the detent projection 62 and the stepping pawl projection 58 from engagement with the driving segment 17, and as a result thereof the segment 17 rotates in a clockwise direction as seen in Fig. 1 under power of the spring 25. When the driving segment 17 returns to normal position with respect to the carriage 20, the projection 33 on lock bar 31 drops into the slot 34 causing the carriage 20 and the driving segment 17 to be locked together and causing the carriage 20 to be unlocked from the lock segment 37. This results in the rota-

tion of the carriage 20 and the segment 17 in a clockwise direction as seen in Fig. 1 to normal position under the power of spring 25A. Magnet 44 is then deenergized to completely restore the switch.

Referring now to Figs. 1, 6, 7 and 8, the framework 10 and the bank contact assemblies 12 will be described in detail. The framework is made up of a plurality of shelves 130 which are positioned and maintained one above another by suitable framework elements. Each of these shelves 130 is adapted to serve as the mounting for one of the switches 11 and the switch 11 is secured and positioned in place by any suitable means, such as screws 131.

The portion of the shelf 130 which is disposed beneath the contact wiper assemblies 113 is arcuately shaped in accordance with the arc described by the tips of the contact wipers 12 during their rotary movement. This arcuate edge of the shelf 130 has a series of radially disposed projections 132, each of which is disposed along a radial line extending from the center axis 14 of the switch 11. The distance between the projections 132 is equal to the distance the contact wiper assemblies 13 are moved when the carriage 20 of the switch is rotated one step.

The shelf 130 is further provided with a pair of laterally projecting arms 133, each of which has a bank locking wing 134 pivotally attached to the end thereof by screws 135. The shelf 130 also has a center arm 136 extending outwardly therefrom which is secured to an arm 137 of one of the wings 134 by a screw 138. The two wings 134 that are mounted on any one shelf 130 are fastened together by any suitable means, such as screw 139. The wings 134 are also provided with a plurality of projections 140 each of which is disposed along a radial line extending through the center axis 14 of the switch 11 of one of the projections 132 of the shelf 130.

The bank assembly 12, which is adapted for use with this switching apparatus, is shown in detail in Figs. 7 and 8 and comprises a block of insulating material 141 which has a series of slots 142, longitudinally disposed along opposite sides thereof. A conductor wire or contact 143 is positioned and maintained in each of the slots 142 by a series of strips of insulating material 144. The strips 144 on each side of the bank are each provided with a metallic reinforcing plate 145 and each strip 144 and plate 145 laterally traverses all of the contacts 143. Each end is then fastened to the insulating block 141 by a rivet 146. The strips 144 and plates 145 are spaced along the assembly 12. When the contact bank assembly 12 is mounted in the framework 10, one of the retaining plates 145 will be disposed opposite each shelf 130. In this way the bare outer surface of the contacts 143 are exposed and unobstructed for contact by the contact wipers 12 of the switch 11. The bottom portion of the bank assemblies 12, as seen in Figure 7, has a diagonally disposed surface from which the terminating ends of the contact rods 143 are exposed. These terminating ends are accessible for connection to such further circuits as are desired. This connection may include an adaptable plug-in type jack such as would permit disconnection and reconnection with relative ease. The terminating end of the contact bank assembly is provided with a suitable retaining plate 147 on either side of the bank assembly and each of which covers a suit-

able insulator 143. These plates and insulators 147, 149 are fastened to the structure by rivets 149.

The width of the projections 132, 140 are adjusted so that they will fit between the retaining plates 145 and 147 of the bank assembly 12. The portions of the retaining plates 145 and 147 which extend forwardly beyond the edge of the insulating block 141 are each notched, the notches in each case being wide enough to engage the thickness of the shelf 130. As will be seen in Fig. 6, when the contact bank assembly 12 engages the arcuately shaped surface of the shelves 130, one of the projections 132 of each of the shelves 130 is positioned between each pair of retaining plates 145 and 147 and the notches of the retaining plates engage the thickness of the shelves 130. After the bank 12 is so positioned, the wings 134 are rotated about their pivots 135 until the projections 140 engage the rearwardly extending portion of the retaining plates 145 and 147. The wings 134 are rotated inwardly an additional amount until the projections 132 and 140 tightly engage the insulating block 141, at which time each pair of wings are fastened together by screws 139 and the projection 137 is fastened to the arm 136 of each of the shelves 130. The contact bank 12 is thereby positioned along a radial line extending from the central pivot 14 of the switch 11. Since the contact wiper assemblies 13 and each switch are adapted to move along such a radial line, and since each of the projections 132 is positioned at one of the rotary steps of the wipers 13, the contact bank which is connected to the framework as described above will be correctly positioned for engagement with the wiper during a selected radial movement thereof.

Having described the invention, what is considered new and is desired to be secured by Letters Patent is:

1. In an electric switch, a wiper, a first member, a second member, a shaft, said members mounted rotatively and adjacently on said shaft, said wiper slidably mounted on said first member, said members having a normal position, means on said members for locking said members together, means for directly rotating said second member a first and a second selected amount, said first member following the rotation of said second member when said second member is rotated said first selected amount, means for unlocking said members and for locking said first member against further rotational movement, means whereby said last means is operated at the completion of the rotation of said second member said first selected amount, means associated with said first and second members for sliding said wiper along said first member, means whereby said sliding means is operated responsive to the rotation of said second member said second selected amount, said second member having a series of holes therein, an indicator arm rotatably mounted upon said shaft, said arm having a projection extending therefrom, said projection capable of engaging any one of said series of holes, means associated with said first means for engaging said arm for causing said projection to engage one of said holes, which of said holes is engaged dependent upon the selected extent of rotation of said second member said first selected amount, said arm thereafter rotated with said second member said second selected amount to indicate said second selected amount.

2. In an electric switch, a base, a first member, a second member, a shaft mounted upon said base, said first and second members mounted rotatively and adjacently on said shaft, a lock bar mounted on said first member, a locking slot in said second member, said lock bar normally biased toward engagement with said locking slot thereby causing said members to be rotatable together, means for directly rotating said second member a first amount and a second amount, a third member rigidly mounted on said base, means for moving said lock bar out of engagement with said locking slot and into engagement with said third member to lock said first member from further rotational movement so that only said second member is rotated said second amount and means whereby said last means is operated when said rotation of said first amount is completed.

3. In an electric switch as claimed in claim 2 said lock bar comprising a resilient spring, one end of said spring being rigidly fastened to said first member, the other end of said spring having projections thereon, said projections extending from said spring in two directions, one of said projections in one direction engageable with said locking slot, said projections in said other direction engageable with said third member.

4. In an electric switch as claimed in claim 3, said third member including an arcuate first element having slots therein, said slots engageable with said lock bar in any rotational position of said first member, and said second means comprising an arcuate second element pivotally mounted on said third member, said second element engageable with said lock bar in any rotational position of said first member and means for pivoting said second element for causing said second element to engage said lock bar, which moves said lock bar out of engagement with said locking slot and into engagement with said slots.

5. In a two motion selecting switch having a wiper carriage supporting a plurality of wiper sets and having a plurality of groups of bank contacts accessible to each wiper, a driving element, means for driving said driving element, a control magnet, a lock bar mounted on said wiper carriage, said lock bar comprising a resilient spring having a normal bias and having projections on one end thereof, locking means, means for controlling said bias to cause certain of said lock bar projections to engage said driving element thereby linking said driving element and said carriage to cause a first movement of the element to move said carriage and wipers into position before a particular group of said bank contacts, means whereby said controlling means is controlled by a first operation of said control magnet, means for controlling said bias to cause said lock bar projections to disengage said driving element and to cause certain of said projections to engage said locking means to lock said carriage to thereby cause further movement of said element to move said wipers to one of the contacts in the particular group, means whereby said last means is controlled by a second operation of said control magnet, means for releasing said wipers and said carriage to cause them to return to normal, and means whereby said release means is controlled by a third operation of said control magnet.

6. In an electric switch, a base, a wiper, a first member, a second member, a shaft mounted on said base, said members mounted rotatively and adjacently on said shaft, a tensioned spring con-

nected to said base and said second member biasing said second member in one rotational direction, a second tensioned spring connected to said first and second members biasing said members in opposite rotational directions, said members having a normal biased position, said wiper slidably mounted on said first member, means on said members for locking said members together, means for directly rotating said second member a first and a second selected amount, means for unlocking said members and for locking said first member from further rotational movement, an electromagnet and an armature therefor, means including said armature whereby said first means is operated when said electromagnet is energized, means whereby said third means is operated when said electromagnet is deenergized at the completion of said rotation of said second member said first selected amount, means associated with said first and second members for sliding said wiper along said first member, and means whereby said sliding means is operated responsive to the rotation of said second member said second selected amount.

7. In an electric switch as claimed in claim 6, ratchet teeth disposed along part of the periphery of said second member, said second means comprising a pawl biased to engage the first of said ratchet teeth and means for operating said pawl a successive number of times in two series, a detent engaging the following ratchet tooth and engageable with said pawl, a release lever mounted on said armature engageable with said detent, means whereby said release lever is operated to engage said detent when said electromagnet is deenergized, means whereby said release lever is operated to withdraw said detent from said ratchet teeth when said electromagnet is energized a second time to restore said switch to normal under operation of said springs, a stop projecting from said second member engaging said release lever when said switch is in said normal position so that said release lever is prevented from withdrawing said detent when said electromagnet is initially energized.

8. In an electric switch, a wiper, a first member, a second member having an arcuate portion thereon, a shaft, said members mounted rotatively and adjacently on said shaft, said wiper slidably mounted on said first member, said members having a normal position, means on the first member normally effective to engage the

second member for locking said members together, means including a series of ratchet teeth disposed along part of the periphery of said arcuate portion for directly rotating said second member a first and a second selected amount, said first member following the rotation of said second member when said second member is rotated said first selected amount, a third member, means operated at the completion of the rotation of said second member said first selected amount for moving said first means out of engagement with the second member, thereby to unlock said first and second members, and into engagement with said third member, thereby to lock said first member from further rotational movement, means associated with said first and second members, including a series of gear teeth disposed along another part of the periphery of said arcuate portion and operated responsive to the rotation of said second member said second selected amount for sliding said wiper along said first member.

9. In an electric switch as claimed in claim 8, said fourth means also including a rack mounted on said wiper, a gear rotatably mounted on said first member and in mesh with said rack, a second gear mounted on the same axis of rotation as said first gear and rotatable with said first gear, said second gear in mesh with said series of gear teeth disposed along part of the periphery of said arcuate portion so that when said second member is rotated said second selected amount said gear teeth rotate said second gear which in turn rotates said first gear which in turn projects said rack in a radial direction.
